Primary Examiner — L. Martinez*(74) Attorney, Agent, or Firm* — Finnegan, Henderson, Farabow, Garrett & Dunner LLP**CLAIM**

The ornamental design for an article of jewelry, as shown and described.

DESCRIPTION

FIG. 1 is a front, bottom perspective view of an article of jewelry, showing my new design in a configuration of use; FIG. 2 is a front, bottom perspective view thereof, showing the article of jewelry in an alternate configuration of use; FIG. 3 is a front elevation view of FIG. 1, wherein the rear elevation view is identical thereto; FIG. 4 is a front elevation view of FIG. 2, wherein the rear elevation view is identical thereto; FIG. 5 is a left side view of FIG. 1, wherein the right side view is identical thereto; FIG. 6 is a top plan view thereof; FIG. 7 is a bottom plan view of FIG. 1; and, FIG. 8 is a bottom plan view of FIG. 2.

The dash-dash lines in the drawings illustrate portions of the article of jewelry that form no part of the claimed design.
